UNITED STATES PATENT OFFICE

149,866

DESIGN FOR A PROTECTING JAR FOR A PAPER MILK CARTON

William J. Fry, Chicago, Ill.

Application August 30, 1946, Serial No. 132,984

Term of patent 14 years

(Cl. D58—25)

To all whom it may concern:

Be it known that I, William J. Fry, a citizen of the United States of America, residing at Chicago, Illinois, have invented a new, original, and ornamental Design for a Protecting Jar for a Paper Milk Carton, of which the following is a specification, reference being had to the accompanying drawings, forming a part thereof.

Referring to the drawings, Fig. 1 is a top plan view of a protecting jar for a paper milk carton embodying my new design; Fig. 2 is a front elevational view; Fig. 3 is a side elevational view; Fig. 4 is a rear elevational view; Fig. 5 is a bottom plan view; and Fig. 6 is a perspective view of the same.

I claim:

The ornamental design for a protecting jar for a paper milk carton, substantially as shown.

WILLIAM J. FRY.
